UNITED STATES PATENT OFFICE.

DAVIDE VALLARINO, OF SAN LEANDRO, CALIFORNIA, ASSIGNOR TO CALIFORNIA FRUIT CANNERS ASSOCIATION, OF SAN FRANCISCO, CALIFORNIA, A CORPORATION OF CALIFORNIA.

CAN-SWITCH.

988,051.

Specification of Letters Patent. Patented Mar. 28, 1911.

Application filed August 22, 1910. Serial No. 578,891.

To all whom it may concern:

Be it known that I, DAVIDE VALLARINO, a citizen of the United States, residing at San Leandro, in the county of Alameda and 5 State of California, have invented certain new and useful Improvements in Can-Switches, of which the following is a specification.

My invention relates to can-switching 10 mechanism, and is applicable in any situation in which a main can-supply has capacity sufficient for plural destinations.

My present object is to provide simple 15 and effective means for automatically diverting successive filled cans from a main carrier to a branch carrier on each side which will convey them to independent sealing machines, thereby effecting economy in time and labor.

20 My invention consists in the novel automatic switching device which I shall now describe and claim.

Referring to the accompanying drawings—Figure 1 is a plan view of my switch 25 showing it thrown over to the left, so that the first can is being carried off by the left branch carrier, while the second can has entered the switch and is about to throw it to the right. Fig. 2 is a plan view showing the 30 switch in a middle position on its course to the right, being impelled thereto by the continued pressure of second can which is itself being deflected to the right branch carrier. Fig. 3 is a plan view showing the 35 switch completely thrown to the right, the second can being on the right branch-carrier and the third can about to enter the other side of the switch.

1 is the main-carrier.

40 2 is the left branch-carrier, and 3 is the right branch-carrier. The branch-carriers are disposed at an angle to the main-carrier, one on either side thereof.

The can-switch is composed of a curved 45 arm 4; another curved arm 5; a link 6 pivotally connecting the adjacent extremities of the two arms; and a base 7 having ears 8 to which the curved switch arms are pivoted at 4' and 5' respectively.

50 The two switch arms 4 and 5 are symmetrical, being of a concavo-convex shape, with their concave faces presented to the direction of travel of the cans on the main-carrier. They are thus oppositely disposed

stated, back to back. Their pivotal centers 4' and 5' are also symmetrically disposed and are so related that the movement of the arms upon said centers, as their connected ends alternately cross and recross the 60 median longitudinal line of the main-carrier, is equal. These arms are, therefore, when in their middle position, as shown in Fig. 2, symmetrically but oppositely disposed with respect to the main-carrier, and 65 the two branch-carriers.

The link 6 which joins the two arms and is pivotally connected to each, as shown, at the points 9 and 10, causes their opposite movement in unison. In order to both limit 70 and lock this movement, the face of the link 6 is provided with a curved lug 11, which at the limit of the throw on either side fits into a correspondingly curved recess 12 in either switch-arm; and this seating of the 75 lug is deep enough to carry the then lower pivotal point of the link beyond a straight line drawn from its then upper pivotal point to the pivotal point of the thrown-back switch-arm with the base, so that the 80 arms are thus locked against further movement. In order to accommodate the head of the thrown-back switch-arm in this locked limit of movement, the adjacent face of each arm is cut out slightly as shown at 85 13; and the head of the arms enters this depression.

The operation of the device is as follows:—The cans, indicated by 14, are supplied to the main-carrier 1 and advance in 90 file toward the switch. Let it be supposed that, as shown in Fig. 1, the position of the arms be such that the arm 5 is thrown back and the arm 4 is thrown forward both to their locked limit. In this position, the head 95 of the arm 5 and the whole of the link 6 are to the left of the center line of the main-carrier, and together they present a continuous smooth surface. The first can having been diverted to the left branch carrier 2, the 100 second can advancing, therefore, contacts to one side of its vertical center with the end of the link and then enters the embrace of the arm 5. It is thus by its continued movement necessarily bodily forced over sidewise as it 105 travels against the then locked faces of the link and the adjacent part of the arm 5, until, by this side movement it reaches that portion of arm 5 which lies to the right of its pivotal center at 5', as shown in Fig. 2, whereupon 110

55 with relation to each other, or, as it may be

its pressure, under the continued advance of the main carrier, swings said arm 5 forwardly, which has the effect of continuing the bodily movement of the can sidewise and 5 over onto the branch-carrier 3. This movement of the can thus resets the switch in its opposite position as shown in Fig. 3 in which said arm 5 is thrown forward and the arm 4 is thrown backward, thereby setting the 10 switch for the third can which by a like pressure and operation is deflected over to the other branch-carrier 2, which has the effect of resetting the switch in its first position. Thus the cans are successively 15 diverted to the left and to the right automatically, and the object of the device is attained.

Having thus described my invention what I claim as new and desire to secure by Letters Patent is—

1. A can-switch comprising a pair of swinging arms, connected to act in unison, said arms being disposed in the line of travel of the cans and adapted by the pressure of 25 successive cans to be thrown alternately to the left and to the right to deflect successive cans to opposite sides.

2. In a can-switching mechanism, the combination with a main-carrier and branch-carriers at an angle to the main carrier at 30 opposite sides thereof, a pair of swinging arms connected to act in unison, said arms being disposed in the line of travel of the cans on the main-carrier and adapted by the pressure of successive cans to be thrown alternately to the left and to the right, to deflect successive cans from the main carrier to opposite branch-carriers.

3. A can-switch comprising a pair of relatively reversed swinging arms, pivotally connected to act in unison, said arms being disposed in the line of travel of the cans and adapted by the pressure of successive cans to be thrown alternately to the left and to 45 the right of the median line of travel of said cans, to deflect the successive cans to opposite sides.

4. In a can-switching mechanism, the combination with a main-carrier, and branch-carriers at an angle to the main-carrier at opposite sides thereof, a pair of relatively 50 reversed swinging arms, pivotally connected to act in unison, said arms being disposed in the line of travel of the cans on the main-carrier and adapted by the pressure of successive cans to be thrown alternately to the left and to the right of the median line of travel of said cans, to deflect successive cans from the main carrier to opposite branch-carriers.

5. A can-switch comprising a pair of relatively reversed, symmetrically pivoted, swinging arms, disposed in the line of travel of the cans and adapted by the pressure of 65 successive cans to be thrown alternately to

the left and to the right to deflect successive cans to opposite sides, and a link pivotally connected with the adjacent ends of said arms and disposed to alternately continue their pressure faces past the median line of travel of the cans.

6. A can-switch comprising a pair of relatively reversed, symmetrically pivoted, swinging arms, disposed in the line of travel of the cans and adapted by the pressure of 75 successive cans to be thrown alternately to the left and to the right to deflect successive cans to opposite sides, and a link pivotally connected with the adjacent ends of said arms and disposed to alternately continue 80 their pressure faces past the median line of travel of the cans, said link having a bearing against said arms alternately, to limit their movement at either side.

7. A can-switch comprising a pair of relatively reversed, symmetrically pivoted, swinging arms, disposed in the line of travel of the cans and adapted by the pressure of successive cans to be thrown alternately to the left and to the right to deflect successive 90 cans to opposite sides, and a link pivotally connected with the adjacent ends of said arms and disposed to alternately continue their pressure faces past the median line of travel of the cans; said link having a bearing against said arms alternately, to limit their movement at either side, the bearing being so disposed as to throw the pivotal centers out of line to lock the parts at said limit of movement.

8. In a can-switching mechanism, the combination of a main-carrier; branch-carriers on opposite sides of the main-carrier at an angle thereto; a pair of curved, relatively reversed, symmetrically pivoted swinging arms disposed in the line of travel of the cans on the main-carrier and adapted by the pressure of successive cans to be thrown alternately to the left and to the right to deflect successive cans to opposite branch-carriers, each of said arms having a recess; and a link pivotally connected with the adjacent ends of said arms and disposed to alternately continue their pressure faces past the median line of travel of the cans, said link having a lug adapted to enter the recesses of said arms alternately to limit their movement to either side.

9. In a can-switching mechanism, the combination of a main-carrier; branch-carriers on opposite sides of the main-carrier at an angle thereto; a pair of curved, relatively reversed, symmetrically pivoted swinging arms disposed in the line of travel of the cans on the main-carrier and adapted by the pressure of successive cans to be thrown alternately to the left and to the right to deflect successive cans to opposite branch-carriers, each of said arms having a recess; and a link pivotally connected 125

- with the adjacent ends of said arms and disposed to alternately continue their pressure faces past the median line of travel of the cans, said link having a lug adapted to enter
- 5 the recesses of said arms alternately to limit their movement to either side, said recesses being deep enough to carry the pivotal centers out of line to lock the parts at the limits of movement.
- 10 10. A can-switch comprising a pair of segmental shaped swinging arms, connected to act in unison, said arms being disposed in the line of travel of the cans and adapted by the pressure of successive cans to be thrown
- 15 alternately to the left and to the right to deflect successive cans to opposite sides.
11. A can-switch comprising a pair of pivotally supported arms, connected by an interposed link to act in unison, said arms
- 20 being disposed in the line of travel of the

cans and adapted by the pressure of successive cans to be thrown alternately to the left and to the right to deflect successive cans to opposite sides.

12. A can-switch comprising a pair of 25 curved arms, a pivotal support for each arm intermediate the ends thereof and a pivotal connection between the adjacent ends of the arms permitting said arms to move by the pressure of succeeding cans alternately in 30 opposite directions upon their pivotal supports.

In testimony whereof I have signed my name to this specification in the presence of two subscribing witnesses.
